STOVE

Clement Ehret, White Plains, N. Y.

Application August 11, 1933, Serial No. 684,650

18 Claims. (Cl. 126—39)

This invention relates to the art of stoves and more particularly stoves employed for cooking purposes and utilizing fuel of various kinds.

One of the objects of the present invention is 5 to provide a stove which may be readily regulated at the will of the cook or housewife to a height which will best suit her particular requirements, and will enable pots and pans on the top of the stove to be easily and conveniently handled and 10 at the same time allow convenient manipulation of cooking pans into and out of the oven.

A further object of this invention is to provide a stove construction wherein the necessity of reaching over any burner on the stove is entirely eliminated through the utilization of a 15 stove body which is rotatable to present any particular burner at the front of the stove at the will of the operator.

According to the present invention, the entire 20 body of the stove is rotatable, the top of the stove and the burners being movable as one, and locked against rotation with respect to one another, so that when a pot is once placed in proper cooperative relation to its burner, it will remain in this 25 position and rotation will not alter this relation. Furthermore, the source of heat is entirely localized with respect to the particular pot and this relation does not change upon rotation of the stove.

Aside from the foregoing generic objects of 30 this invention, the same includes a number of novel features, all of which cooperate, as herein-after more fully described, to produce a stove convenient to work at, economical and simple to operate, and efficient in the fulfillment of its intended purposes.

These will be apparent from the hereinafter detailed description and claims, when read in conjunction with the accompanying drawings.

The accompanying drawings illustrate different 40 practical embodiments of the invention, but the constructions therein shown are to be understood as illustrative, only, and not as defining the limits of the invention.

Figure 1 is a perspective view of a stove embodying the present invention.

Figure 2 is a central vertical section of the stove shown in Figure 1.

Figure 3 is a fragmental section on the line 45 3—3 of Figure 2.

Figure 4 shows the present invention as incorporated in a coal range.

Figure 5 is a section on the line 5—5 of Figure 4.

Figure 6 shows a modified form.

As hereinbefore pointed out, the present invention may be used with stoves employing fuels of various kinds, and, for the purpose of illustration, I have chosen to show in Figures 1, 2, 3 and 6, the invention as embodied in a gas range.

Referring to these figures, 1 designates the body of a stove. Heretofore, stove bodies have generally been provided with legs resting directly on the floor to rigidly support the stove body in position. According to the present invention, in contradistinction, this stove body is mounted for rotation and vertical adjustment. The details of construction and shape of the stove parts may vary without departing from this invention, but, for the purpose of illustration, I have shown the stove body 1 as of circular form 10 embodying a housing 2 having a closed bottom 3 and closed top 4. Within this housing is positioned an oven 5 which preferably extends for the full diameter of the housing and is shown as 15 open at its opposite ends although it may have door openings in its sides as well. Each of these openings has a door 6 so that access may be had from various sides thereof. The oven is spaced 20 from the wall of the housing in any appropriate manner and is provided with a turntable bottom 7 mounted to rotate in any suitable way as on a center spindle or peripheral rollers, so that when 25 a baking pan is resting on a turntable, it may be readily rotated by engaging the pan with a 30 fork or spoon and turning it.

Heat is supplied beneath the oven for baking from a burner 8 to which gas is led through a valve 9. This valve may be of any suitable kind, such as an ordinary plug cock, but the 35 valve stem 10 thereof is preferably arranged so as it extends to the opposite sides of the stove and beyond the wall of the housing and each end of this valve stem is provided with a handle 11 as shown in Figure 1 to permit of the operation 40 of the valve from each side of the stove.

Below the valve 9, the gas supply pipe is provided with a T 12 from which extends a branch pipe 13 leading to a header 14 positioned adjacent the upper part of the housing and extending entirely around the top of the stove. This 45 is the main gas header for the various burners 15. Four of these burners are shown, but any number may be provided. They may be of the 50 usual type and are fed from the header 14 through conventional cocks 16. Within the several branch pipes leading through the cocks to the burners 15, there may be included the usual gas and air mixing chamber, but for simplicity, 55

these have been omitted from the drawings because they are conventional and well known.

Gas fed from the T 12 is thus passed to the header 14 and may be fed to the burners selectively by manipulating the appropriate cocks 16. Below the T 12, there is provided a swivel connection 17, the axis of which is coaxial with the stove body. This swivel is such as to permit rotation of the stove body while at the same time an uninterrupted feed of gas. Any suitable swivel may be used in this connection, but, for the purpose of illustration, the connection is shown as embodying a channelled tapering plug 18 fitting into a correspondingly shaped chambered member 19 with appropriate gas channels so as to permit of rotation of the stove body and still feed the gas. The oven 5 also has a broiling burner 8' therein fed through a branch pipe 13'. A valve 9' is included in this pipe and the valve stem 10' extends to opposite sides of the stove and has handles 11' by which the flow of fuel to the burner 8' is controlled.

As hereinbefore stated and hereinafter fully explained, this stove body is not only adapted to be rotated, but also to be raised and lowered and the gas connection must therefore be such as to permit of both of these operations. Consequently, the connection between the T 12 and the main supply pipe 20 is provided with not only the swivel connection 17, but also additional swivel connections 21, 22 and 23 to permit of its operation while using closed pipe connections. Swivel connection 21 is shown in detail in section in Figure 3 and the connections 22 and 23 are of the same character, although all of these swivel connections may be of any other suitable construction providing that they will permit continuous feed of gas and at the same time the adjustment and rotation to which I have referred. The use of the swivels 21, 22 and 23 as shown is to permit the raising and lowering while maintaining a closed arrangement. Flexible tubing may be used as a connection but pipe and swivel connections are shown as preferable.

The supply of air to support combustion at the burners 8 and 8' may be obtained in any suitable way as by providing perforations in the bottom or in the side walls of the housing 2 and oven 5 and to preclude the radiation of too much heat through the walls of the housing they may be insulated with spaced interlinings or may be provided with appropriate insulation such as asbestos and the like, so that if the cook comes in contact with the wall of the housing when the oven is in operation, she will not be burned. These and other forms of insulation for use in connection with ovens are so well known that it is not thought necessary to specifically illustrate the same.

The waste products of combustion from the oven may be disposed of in any suitable way as, for example, through the bottom of the oven, as hereinafter described with reference to Figures 4 and 5, or through the side of the housing as in Figure 6, but in Figures 1 and 2 I have shown the top wall 4 of the housing as having an axial outlet pipe 24 which has a sliding fit into a sleeve 25 of a warming oven housing 26. This warming oven housing is positioned above the body of the stove and will presently be explained in detail.

In order to mount the body of the stove which, in the construction shown, is all contained within and mounted on the housing 2, said housing is provided at its bottom with an annular ball

race 27 adapted to cooperate with a similar ball race 28 and between these two races are positioned a series of ball bearings or roller bearings 29. The lower ball race 28 is mounted on any suitable form of base. This base may widely vary in construction depending upon individual taste and design, but it embodies fundamentally means for supporting the lower ball race for vertical adjustment with means for accomplishing such adjustment. However, while an antifriction mounting is preferable for the stove body, any other suitable mounting may be employed without departing from this invention.

In the form of the invention which I have chosen to show for illustrative purposes, the lower ball race is provided with a plurality of depending threaded posts 30 which extend downwardly and into the hollow legs 31 of a base 32. The base is shown in the form of a casting with four hollow legs and consequently four threaded posts 30 are employed. Each leg of the base is formed as shown in Figure 2 to support a sprocket 33 against vertical movement, and each sprocket is provided with a threaded hub through which one of the posts 30 extends. Thus, there are four posts with four sprockets and it will be apparent that upon rotation of the sprockets the posts will be vertically moved to impart corresponding movement to the body of the stove and constitute an adjustable support therefor. In order to synchronize the operations of these sprockets, they are encircled by a sprocket chain 34, which also passes about and in mesh with an operating sprocket 35. This operating sprocket is mounted on a stub shaft 36 to which is fixed a bevel gear 37 meshing with a bevel gear 38 operable by any suitable prime mover operable by power or manually and located in any convenient position but shown as a crank or hand wheel 39. By operating this crank, the sprocket chain 34 is caused to function and all of the sprockets 33 are rotated to rectilinearly shift the threaded posts. Thus the whole stove housing including the section 28 which is movable, is made vertically adjustable. This is accomplished through the manipulation of unitary means shown illustratively in the form of a crank or hand wheel 39. By mounting the stove body upon the ball race 27, it is free to rotate with this race without appreciable friction and yet with sufficient friction that it will not inadvertently turn.

If desired the operations of raising and lowering the stove body may be counterbalanced in various ways. For example, compression springs 30' may be coiled about each of the posts 30, as indicated in Figure 2, to seat on the base 32 and bear upwardly against the race 28 and thus counterbalance the weight of the stove body. These springs may be enclosed in suitable collapsible casings if desired or may be positioned within the legs.

The base 32 is adapted to rest firmly upon the floor in a stationary rigid position and is provided with appropriate means such as a bracket 40 or brackets 40 which extends upwardly at the back of the stove and serve as a support for the warming oven housing hereinbefore referred to.

This housing may be of any appropriate shape and is preferably flared outwardly at its bottom as indicated at 41 to form a hood for collecting the waste products of combustion, vapors and odors and passing them upwardly and out of a pipe 42 leading to the chimney. To permit of this, the bottom of the housing 26 is provided

with openings 43 shown in Figure 2. Products of combustion from the housing 2 of the stove body are led into the housing 26 through the outlet pipe 24 and the sleeve 25 and from thence 5 pass out through the pipe 42. The heat passing through the housing 24 is availed of for useful purposes by positioning within said housing 26 a warming oven 44 as shown in Figure 2. This oven has a door or doors 43 at its front and 10 serves as a warming space for plates and to keep cooked articles warm until they are served. This oven may be thus heated conjointly by the waste heat from the burners at the top of the stove and by the waste heat from the oven and does 15 not require its own individual source of fuel supply for heat.

Oven 44 may have, if desired, heating and broiling burners 8² and 8³, respectively, fed from a pipe 20' leading from fuel pipe 20 and including 20 valves 20² and 20³ with handles 20⁴ and 20⁵ to selectively control the flow of fuel to said burners.

In the structure as described, the warming oven and its housing are stationary with respect to the 25 stove pipe 42 and this stove pipe may therefore be directly connected with the chimney in the usual way. Similarly, the base is rigid and stationary and serves as a stationary and rigid support for the warming oven. It is only the intermediate 30 stove body, i. e., ovens, associated burners and stove top which are rotatable, but all these parts rotate as a unit and their relative positions are at all times the same. For instance, if the pot is placed over any one burner, the stove may 35 be rotated without in anywise affecting the relative relation between the pot and the burner for the burner rotates with the pot and vice versa and the oven rotates with all the burners, while the warming oven and the base remain stationary.

The products of combustion have been shown in Figures 1 and 2 as led off through coaxial piping connections 24—25, but if desired they 45 may be led off as shown in Figure 6. Here the housing 1 is shown as provided near its top with openings 100 communicating with the interior of a manifold 101 having flanges 102 interfitting with guides 103 on the housing. An outlet pipe 104 is provided at the back of the manifold and 50 extends upwardly into sliding connection with a sleeve 105 which leads to the warming oven housing 26 and corresponds to sleeve 25 of Figure 1. This structure permits the stove body to be both vertically adjusted and rotated, but the 55 outlet 104 and sleeve 105 hold the manifold against rotation.

For the sake of convenience, a water pipe 45 is secured to bracket 40 and is supported thereby and above the top of the stove body. This pipe 60 has a pivoted spout 46. The flow of water through the spout is controlled by a suitable valve and if desired the parts may be so arranged that when the spout is pulled down into horizontal position, the valve will be opened to permit water 65 to flow through the spout, whereas when the spout is raised into the vertical position, the water will be shut off. The spout of course is stationary with respect to the rotatable stove body, so that the stove body may be turned to position any 70 pot thereon under the spout.

Convenient storage space may be provided in the form of cabinets 47 provided with brackets 48 adapted to be secured by pins or slotted connections to the base 32 or to the section 28 to 75 mount the cabinets thereon. These cabinets may

have legs, extensible or not as required to assist their support, but such legs are not generally necessary. Pots, pans and other cooking utensils or foodstuffs may be stored in these cabinets, which may be of any number.

I have hereinbefore described in detail the present invention as incorporated in a gas range. In an electric range, the problem is simpler, because the wires to supply the current can be led to the burners more readily than piping connections. However, oil or other liquid fuel, such as kerosene, may be fed similarly to the feed of gas as shown. The present invention may, moreover, be used in conjunction with a coal range and in Figures 4 and 5, I have shown the invention incorporated in a stove of this kind.

With reference to these figures, the fire pot is designated 49 and the oven 50, and both of these are contained within a housing 2 which corresponds to all intents and purposes to the 20 housing 2 of the gas range. The smoke pipe, however, instead of going out at the top is shown as extending out of the bottom and is designated 51. It is arranged axially of the stove and has a sliding connection with a sleeve 52 rigidly supported on the base 31, so that the stove body can turn on the ball races 27 and 28 and can be raised and lowered in the same manner as hereinbefore described. The details of the coal stove are not material to this invention except that if the 30 smoke is led out at the bottom as shown a somewhat different draft arrangement than that usually employed is desirable. The oven 50 is directly adjacent the fire box on one side, but at its opposite side, bottom, back and top are spaced 35 from the walls of the housing 2.

A plate 54' extends along the top of the oven and between the oven and the back wall of the housing, but leaves a down draft opening 53. This opening is controlled by a damper 54, the 40 stem 55 of which extends to the outside of the stove for manual operation. When the damper is in the position of Figure 4, the smoke and waste products of combustion pass from the fire pot directly down through the draft hole 53 and 45 out through the pipe 51 to the chimney. When it is desired to bake in the open, however, the damper 54 is operated to close the opening 53 and the heat from the fire pot is then required to circulate across the top of and about the oven 50 and under the bottom thereof before reaching the smoke pipe 51 and thus heats the oven for baking or roasting.

The design of a coal range constructed in accordance with the present invention may vary 55 within wide limits, and I have not considered it necessary to go into detail on this structure as the fundamental feature of the present invention as here applied is the same as in Figures 1 and 2 in that the body of the stove is rotatable with 60 respect to a rigid base in order to place the various parts of the top of the stove within convenient access to the cook and at the same time, the body of the stove may be raised and lowered into the most convenient position.

It will of course be understood that if desired the smoke pipe may be led out of the coal stove at the top instead of the bottom or the waste products of combustion from the gas or electric stove may be led out from the bottom instead 70 of the top. These and other features shown with respect to the two stoves in the accompanying drawings are applicable to stoves utilizing any fuel within the scope of this invention.

It will be apparent from the foregoing de- 75

talled description that there are among the outstanding features of this invention hereinbefore described two which are of great practical importance. The first is that a stove may be regulated into any desired elevation depending upon the requirements of the particular user, and another is that the whole body of the stove may be rotated so that at no time is the user required to reach over the top or across to the back of the stove for any purpose. The header 14 provides a convenient handle for rotating the stove as it may be grasped and turned when desired.

It is of course to be understood that while I have shown the stove circular in Figures 1 and 2 of the accompanying drawings and square in Figures 4 and 5, that this shape may be varied according to the dictates of design without departing from this invention and that the various parts may be proportioned other than as shown. Similarly, while I have disclosed a sprocket and threaded post arrangement with co-operating ball races as a means for raising and lowering the stove body and to provide for this rotation that other forms of apparatus may be employed for the accomplishment of this result, but, in any event, it is desirable that the raising and lowering of the stove body be accomplished by unitary means in the form of an appropriate prime mover either manually or power operated in order that the vertical adjustment may be efficiently carried out.

I have in the drawings shown certain features of novelty which will be applicable to conventional stoves. For example, it will be apparent that the turntable in the oven and which may constitute the whole or a part of the oven bottom may be employed in any stove and claims to this feature per se are to be construed accordingly.

The foregoing detailed description sets forth the invention in its preferred practical form and the invention is to be understood as fully commensurate with the appended claims.

Having thus fully described the invention, what I claim as new and desire to secure by Letters Patent is:

1. A stove embodying a stationary base, and a stove body mounted for rotation on and supported by said base, said rotatable body comprising a source of heat supply, a stove top arranged above and rigid with respect to this source of heat supply, an oven within said stove body, said oven being open at its opposite ends, a door for closing each end of the oven, a source of heat supply for the oven, a valve for controlling the feed of fuel to said last named source of heat supply, and valve operating handles operatively connected to said valve and one of which handles is positioned exteriorly of the stove body and adjacent each oven door.

2. A stove embodying a stationary base, a warming oven housing positioned in spaced relation above and fixedly supported by said base, a flue pipe leading from said warming oven housing, a stove body positioned between the base and the warming oven housing and mounted for rotation on said base, said stove body comprising a baking oven, a source of heat therefor, and a conduit leading from the center of the stove body to the warming oven housing whereby the waste products of combustion from the baking oven will be circulated through the warming oven housing prior to exit through the flue pipe.

3. A stove embodying a stationary base, a

warming oven housing positioned in spaced relation above and fixedly supported by said base, a flue pipe leading from said warming oven housing, a stove body positioned between the base and the warming oven housing and mounted for rotation on said base, said stove body comprising a baking oven, a source of heat therefor, and a conduit leading from the stove body to the warming oven housing, whereby the waste products of combustion from the baking oven will be circulated through the warming oven housing prior to exit through the flue pipe, said conduit including a slip connection to permit variation in the length thereof, and means for raising and lowering the stove body with respect to the stationary base and warming oven housing.

4. A stove embodying a stationary base, a stove body mounted on said base for vertical movement, and means for raising and lowering said stove body with respect to the stationary base, said stove body comprising a source of heat supply supported on the stove body to be raised and lowered therewith, and means for supporting cooking receptacles in cooperative relation to the heat source.

5. A stove embodying a stationary base, a supporting member positioned on and supported by the stationary base, means for raising and lowering the supporting member with respect to the base, and a stove body, including a source of heat supported on the stove body to be raised and lowered therewith, said stove body being rotatably mounted on said supporting member.

6. A stove embodying a stationary base, a stove body mounted on said base for rotation with respect to the base, means for raising and lowering said stove body with respect to the base, a fuel burner supported by the stove body, a source of fuel supply, and piping connections between the source of fuel supply and the burner, said piping connections including at least one universal joint to permit the undisturbed feed of fuel through closed piping connections irrespective of the movement of the stove body.

7. A stove embodying a stationary base, a stove body rotatably supported on said base and comprising an oven and a source of heat supply therefor, a stationary oven housing positioned above the stove body and rigid with respect to the base, and an outlet duct for waste products of combustion from said source of heat supply, said outlet duct being positioned coaxially of the axis of rotation of the stove body and leading from the stove body to the stationary oven housing, and a flue pipe leading from said stationary oven housing.

8. A stove embodying a stationary base, and a stove body mounted for rotation on and supported by said base, said rotatable body comprising a source of heat supply, means for supporting cooking receptacles in cooperative relation to said source of heat supply, a stationary oven housing supported by the base independently of the rotatable stove body and spaced above the latter to receive and utilize waste heat from the stove body.

9. A stove embodying a stationary base, a stove body mounted on said base for vertical movement with respect thereto and comprising an oven and an associated source of heat supply, an outlet conduit for waste products of combustion from the oven, said conduit having therein a slip connection to permit the stove body to be raised and lowered while the conduit remains operative, and means for raising and lowering the stove body.

10. A stove embodying a stationary base, a supporting member positioned on and supported by

- the stationary base, means for raising and lowering the supporting member with respect to the base, a stove body, including a source of heat, rotatably mounted on said supporting member, and an outlet conduit for waste products of combustion leading from the stove body, said conduit having a yieldable connection with the stove body to permit said body to raise and lower and rotate while the conduit remains operative.
- 10 11. A stove embodying a stationary base, a stove body mounted for rotation on and for vertical movement with respect to said base and having a fuel burner, a fuel feed pipe leading to said burner and having therein extensible swivel connections to permit rotation and raising and lowering of the stove body without interfering with the continuous supply of fuel to the burner.
12. A stove embodying a stationary base, a stove body supported on said base to be raised and lowered with respect thereto, a fuel burner supported on said stove body to raise and lower therewith, and a fuel supply pipe leading to the burner and including an extensible connection to permit the stove body to be raised and lowered without interfering with the supply of fuel to said burner.
13. A stove embodying a stationary base, an annular track mounted on the base for vertical movement relative thereto, means for raising and lowering said track, and a stove body mounted on and supported by said track for rotation thereon.
14. A stove embodying a stationary base, an annular ball race mounted on the base for vertical movement relative thereto, means for raising and lowering said ball race, a stove body provided with a complementary ball race, and ball bearings positioned between said ball races and serving to support the stove body for rotation.
- 40 15. A stove embodying a stationary base, an annular track mounted on the base for vertical movement relative thereto, means for raising and lowering said track for rotation thereon and including an oven, and an outlet for conveying away waste products of combustion from the oven, said conduit including an extensible and rotatable connection to permit the stove body to be raised, lowered and rotated while the conduit remains operative.
16. A stove embodying a stationary base, an annular track mounted on the base for vertical movement relative thereto, means for raising and lowering said track, a stove body mounted on and supported by said track for rotation thereon, an oven housing mounted rigid with respect to the base and spaced above the stove body, and a conduit for waste products of combustion extending axially from the rotatable stove body to the stationary oven housing and including a slip connection to permit the stove body to be rotated, raised and lowered while said conduit remains operative.
17. A stove comprising a stationary base, a stove body rotatably supported on said base and having an oven and a source of heat supply therefor, a tubular conduit leading from said source of heat supply and through which fuel may be fed to the source of heat supply, said conduit including a rotatable union to permit of rotation of the stove body without interfering with the continued feed of fuel.
18. A stove comprising a stationary base, a stove body rotatably supported on said base and having an oven and a source of heat supply therefor, a feed line for feeding fuel to the source of heat supply, said feed line including a rotatable connection to permit of rotation of the stove body without interfering with the continued feed of fuel.

40
CLEMENT EHRET.
